UNITED STATES PATENT OFFICE.

FREDERICK HARDY, OF COLUMBIA, TENNESSEE.

NECKTIE-PRESS.

1,123,736.

Specification of Letters Patent.

Patented Jan. 5, 1915.

Application filed August 22, 1913. Serial No. 736,197.

To all whom it may concern:

Be it known that I, FREDERICK HARDY, a citizen of the United States, residing at Columbia, in the county of Maury and State of Tennessee, have invented certain new and useful Improvements in Necktie-Pressers, of which the following is a specification.

The present invention relates to new and useful improvements in garment pressing devices, and has particular reference to that type of such articles which are employed in pressing neck-wear and the like.

As its principal object, this invention aims to provide a device of the character above set forth consisting in a pair of interfitting clamping plates which are equipped with a spring element for forcing them into engagement with one another.

An object of equal importance with the foregoing is to form the two clamping plates and their spring element in such manner that the pressure exerted upon the neck wear will be substantially equal throughout the entire length of the clamping plates.

A still further object is to construct the device of this invention with such regard to number, proportion and arrangement of parts that it may be cheaply manufactured, will be durable and efficient in its action, and may be quickly and conveniently employed in pressing the creases and the like out of ribbons, neck-ties and any other similar apparel.

A yet further object is to construct the two clamping plates in such manner that the spring element by which they are urged into clamping engagement with one another may be detachably applied, so that springs of various sizes and strength may be manufactured to accompany each device, thus making it possible for the user to accommodate the clamping plates to ties or ribbons and similar articles of light or fine texture.

A still further object is to form the terminals of the clamping plates at which the tie is inserted with oppositely beveled lips, which will act in the manner of a flat iron in spreading the fabric as it is inserted, removing the creases and wrinkles, so that when the fabric passes into the press and between the clamping plates, it will be entirely smooth.

The above and additional objects are accomplished by such means as are illustrated in the accompanying drawings, described in the following specification and then more

particularly pointed out in the claims which are appended hereto and form a part of this application.

With reference to the drawings, wherein 60 I have illustrated the preferred embodiment of my invention as it is reduced to practice, and throughout the several views of which similar reference numerals designate corresponding parts,

Figure 1 is a perspective view illustrating the clamping plates in clamping relation to one another with a neck tie interposed between their clamping faces. Fig. 2 is a perspective view of the clamping plates 70 in disassembled relation; Fig. 3 is a transverse section taken medially through Fig. 1; Fig. 4 is a detail view of the preferred form of spring; and Fig. 5 is a detail view of a modified form of spring which is in- 75 interchangeable with that shown in Fig. 4.

Before proceeding with the description of the drawings, it is desirable to emphasize the fact that while the device of this invention has been designed with particular reference to the needs of neckwear, and especially ties, it may, nevertheless, be employed with equal efficiency in pressing ribbons, lace collars, and other wearing apparel of a similar nature.

Coming now to the description of the drawings, the numerals 10 and 11 designate respectively and as entireties the upper and lower clamping plates which are held in assembled clamping relation by means of a 90 leaf spring 12. The upper clamping plate 10 consists essentially in an elongated metal plate, preferably nickel. The forward terminal of the member 10 is formed in the nature of a triangular tongue, the edges of 95 which are bent upwardly and at an angle to the plane of the body portion, producing the inclined lips or beveled edges 13 and 14, the purpose of which will be hereinafter more fully disclosed. The longitudinal edges of 100 the plate 10 are bent upwardly and at right angles to the body portion, producing the side walls 15 and 16 which are formed with transversely alined recesses which are indicated at 17 and are in the preferred embodiment disposed approximately centrally of the members 15 and 16. The side walls 15 and 16 terminate a slight distance short of the rear end of the body plate to permit the formation of laterally extending hinge lugs 110 19 and 20 which are adapted for insertion in receiving recesses 21 and 22 formed at the

rear terminal of the side walls 23 and 24 formed on the longitudinal edges of the lower clamping plate 11, as will be readily observed upon reference particularly to Fig. 2. It may be well to explain at this point that the side walls 23 and 24 are provided not only to permit the formation of a hinge connection between the plates, but are also designed to hold the upper plate 10 against transverse shifting when the two plates are in clamping relation, in the manner shown in Fig. 1. The forward terminal of the plate 11 is also formed in the nature of a V-shaped tongue, and is equipped with downwardly beveled lips 25 and 26, which coact with the members 13 and 14 in the production of a flared mouth or throat in which the tie is inserted in a manner to be hereinafter described.

In applying the tie or similar article to the clamping device above described, this invention employs a wedging slat 27 which, in the preferred embodiment, is formed from an elongated strip of light wood, the terminal of which is preferably square as at 28. Upon reference to Fig. 1, the manner in which the tie is doubled around the member 27 and inserted through the throat to lie between the clamping plates 10 and 11 will be readily understood. As previously set forth, there has been provided a leaf spring 12 which is employed in holding the plates 10 and 11 in the desired clamping engagement. This spring 12 is inserted beneath the cross rod 29 terminally mounted in apertures formed adjacent the upper terminals of fastening arms 30 and 31 formed integrally with a U-shaped bracket 33, the bight portion of which engages against the under face of the lower clamping plate 11, as clearly indicated by dotted lines in Fig. 2.

Relative to the particular formation of the spring member 12, it is to be noted that in the preferred embodiment this element consists of a relatively wide sheet or plate of steel which is longitudinally curved to produce a central transversely extending depression 34 and a pair of upwardly curved terminal lips 35 and 36. The central depression 34 is adapted to receive the rod 29. As regards the application of the spring to the clamping plates, it will be apparent that the upwardly curved edge 35 may be readily slid along the smooth face of the upper clamping plate 10 until the rod 29 is retained in the transverse depression 34.

It has been found desirable in practice to manufacture the pressing device of the present invention with two springs of different sizes, as illustrated in Figs. 4 and 5. The apparent desirability of this feature lies in the fact that when neck-ties or similar articles are pressed, a smaller spring must be employed, since the space comprehended between the members 10 and 11 will be relatively

large, and that since this spacing of the members 10 and 11 is considerably reduced when a ribbon or similar like fabric is inserted, it is necessary to employ a spring possessed of a greater degree of curvature in order that the desired clamping engagement may occur between the plates 10 and 11.

The actual construction and arrangement of the several parts of this invention being thus described, it now remains to call attention to the many advantages resulting from the novel form of structure employed. In this connection, it is to be noted that there has been provided a single compressing spring which engages the clamping plates 10 and 11 at two longitudinally spaced points and engages the rod 29 at its central point. There is thus produced a substantial pivotal connection, and it is obvious that the pressure upon the tie or other fabric will be equalized throughout the entire length of the clamping plates. It is desirable to also direct attention to the fact that the operation of inserting the member 27 and the fabric between the clamping plates is greatly facilitated by the flared mouth or throat produced by the oppositely inclined lips 13 and 14, and 25 and 26.

It is to be observed that the oppositely inclined lips 13 and 14 and 25 and 26 constitute one of the most important features of this invention, for being pointed and oppositely beveled they act to press out the wrinkles and creases of the entering fabric as would a pair of flat irons applied to opposite sides of a piece of cloth. This action is materially facilitated by the hinged lugs 19 and 20, which obviously prevent the rear terminals of the upper plate from swinging downwardly with resultant opening of the mouth formed by the members 13 and 14, 25 and 26. It will now be seen that the slat member 27 performs the office of a wedge when the tie has been wound about it and is inserted within the flared mouth of the device. Explanatory of this statement, it is to be noted that when the slat is first inserted in the flared mouth, the forward terminal of the upper plate 10 will be lifted slightly from the lower plate 10 against the tension of the spring 12. As the slat moves inwardly, however, the plate 10 is swung on the member 29 as a pivot, and gradually assumes a parallel relation to the lower plate 11.

In reduction to practice, I have found that the form of my invention illustrated in the drawings and referred to in the above description as the preferred embodiment is the most efficient and practical; yet realizing that the conditions concurrent with the adoption of my device will necessarily vary, I desire to emphasize the fact that various minor changes in details of construction, proportion and arrangement of parts may

be resorted to, when required, without sacrificing any of the advantages of my invention, as defined in the appended claims.

What I claim is:—

- 5 1. In a device of the character described, a pair of co-acting clamping plates having a hinge connection at their rear terminals, oppositely inclined lips formed at the forward terminals of the plates producing a flared mouth, a wedge slat adapted to be inserted in the flared mouth, and a removable spring element for normally urging the plates into clamping relation with the slat.
- 10 2. In a device of the character described, a pair of co-acting clamping plates having a hinge connection at their rear terminals, a flared mouth formed at the forward terminals of the plates, longitudinally extending side walls formed on the plates, the walls of one plate being adapted to engage against the inner faces of the walls of the second plate, a removable spring element for normally urging the plates into clamping relation, and means for maintaining the spring element in operative position, said means including a U-shaped bracket having apertures formed at the terminals of its arms and disposed above the plane of the side walls, and a rod extending transversely of the clamping plates and having its terminals mounted in the said apertures.
- 15 3. In a device of the character described, a pair of co-acting clamping plates having a hinge connection at their rear terminals, a wedge slat insertible between the clamping plates, a removable spring element for urging the plates into clamping engagement with the slat, and means for holding the spring element in operative position, said means including a U-shaped bracket having its bight portion in engagement with the under face of the lowermost clamping plate and having its arms terminally apertured and extending above the plane of the upper clamping plate, a rod extending transversely of the clamping plates and having its terminals mounted in said apertures, the spring element being insertible between the uppermost clamping plate and the said rod.
- 20 4. In a device of the character described, a pair of co-acting clamping plates, oppositely inclined lips formed at the forward terminals of the plates producing a flared mouth, a wedge slat adapted to be positioned between the plates by insertion through said mouth, and a removable spring element for normally holding the plates in clamping position.
- 25 5. In a device of the character described, a pair of co-acting clamping plates having a hinge connection at their rear terminals, the longitudinal edges of the plates being up-turned whereby the up-turned edges of
- one plate will embrace the up-turned edges of the other for holding the second-mentioned plate against lateral movement, yieldable means for normally holding the plates in clamping relation, and a wedge slat insertible between the plates, said slat being adapted to move completely through the space between the plates whereby both terminals of the slat may project beyond the terminals of the plate.
- 30 6. In a device of the character described, a pair of co-acting clamping plates having a hinge connection at their rear terminals but being so connected that the space between them is not obstructed and having their longitudinal edges up-turned, whereby the up-turned edges of the lower plate embrace the up-turned edges of the upper plate for holding the upper plate against transverse movement, a transverse rod carried by the lower plate and positioned above the up-turned edges thereof, and a bow-shaped spring member insertible between the rod and the upper plate for holding the plates in clamping relation.
- 35 7. In a device of the character described, a pair of co-acting clamping plates, a rod carried by the lowermost plate and extending above the upper edge of the upper plate, and a bow-shaped spring interposed between the rod and the upper plate for yieldably holding the plates in clamping relation, said spring having a transverse channel formed at an approximate central point, said channel being adapted to receive the rod, whereby the spring is held against longitudinal movement.
- 40 8. In a device of the character described, a pair of co-acting clamping plates having their longitudinal edges up-turned whereby the up-turned edges of the lower plate embrace the up-turned edges of the upper plate for holding the two plates against relative transverse movement, the up-turned edges of the lower plate being provided at their one terminal with transversely alined notches, laterally extending hinge lugs formed on the upper plate at one terminal thereof and adapted to be inserted in the notches, whereby the upper and lower plates may be hingedly connected, a substantially bow-shaped spring, a rod member attached to the lower plate and extending above the upper edge thereof, said spring being freely interposed between the rod and the upper plate for normally holding the upper and lower plates in clamping relation.
- 45 9. In testimony whereof I affix my signature in presence of two witnesses.
